UNITED STATES PATENT OFFICE.

JOHN TOWNSEND TRENCH, OF DUBLIN, IRELAND.

ADJUSTABLE WRENCH.

SPECIFICATION forming part of Letters Patent No. 520,094, dated May 22, 1894.

Application filed December 4, 1893. Serial No. 492,679. (No model.) Patented in England September 8, 1893, No. 16,729.

To all whom it may concern:

Be it known that I, JOHN TOWNSEND TRENCH, a subject of the Queen of Great Britain, residing at Dublin, in the county of Dublin, Ireland, have invented a new and useful Improvement in Adjustable Spanners or Wrenches, (for which I have obtained a patent in Great Britain No. 16,729, bearing date the 8th of September, 1893,) of which the following is a specification.

My invention relates to adjustable spanners or wrenches, and it consists essentially of a grip lever pivoted to the adjustable jaw and adapted to engage with the shank carrying the fixed jaw, the object being to facilitate the adjustment of the movable jaw of a spanner or wrench in a more ready and efficient manner than is at present known. I attain this end in the manner shown in the accompanying drawings, in which—

Figure 1 is a view in elevation of my improved adjustable spanner or wrench with the gripping lever closed to lock the adjustable jaw to the shank carrying the fixed jaw, and Fig. 2 is a similar view showing the gripping lever open. Fig. 3 is a view in back elevation of the said spanner or wrench. Fig. 4 is a broken view in cross section on line $x-x$, Fig. 2, and Figs. 5, 6 and 7 are broken views in elevation showing another form my invention may assume.

Similar parts are marked with like letters of reference throughout the several views.

The fixed jaw A of the spanner or wrench is formed on or attached to a shank B which is made of a rectangular shape in cross section with parallel faces for the adjustable jaw to slide on. The adjustable jaw A' is slotted to adapt it to slide on the shank B and it has in the under side of its front part a recess a' in which is pivoted a gripping lever C, the gripping face c of which is toothed or serrated to engage with similar teeth or serrations on the adjacent face b of the shank B. These teeth or serrations are very fine so as to give the greatest possible nicety of adjustment. The lever C has a suitably shaped handle C', and the shank B carrying the fixed jaw A has an extension forming a handle B'. To prevent the front edge of the slot in the adjustable jaw A' from catching in the teeth or serra-

tions on the face b of the shank B, a small guide piece a^2 is screwed or otherwise fixed to the inner side of the slot in the adjustable jaw A' to engage with one side of a slot or recess b' formed in the shank B and so keep the front edge of the slot clear of the teeth or serrations on the face b of the shank B, as shown more clearly by Fig. 4 of the accompanying drawings. As a modification of this construction the lever C may be pivoted to an extension A² on the back of the adjustable jaw A' as shown by Figs. 5, 6 and 7, the handles B' and C' being shaped accordingly, which construction leaves the jaws clear and thus makes the spanner or wrench more handy for use in confined spaces. The gripping face c of the lever C may be either slightly curved as shown by Figs. 1 and 2, or flat as shown by Figs. 5 and 6.

To adjust the jaw A' of the spanner or wrench the gripping face c of the lever C is first disengaged from the adjacent face b on the shank B, and then the said jaw is moved on the said shank until the nut or bolt is gripped between it and the fixed jaw. The handles C' and B' of the gripping lever C and the shank B respectively are then clasped by the hand bringing the teeth or serrations on the locking face c of the lever C into contact and engagement with the teeth or serrations on the face b of the shank B thereby firmly interlocking the one with the other. I prefer to shape the back end of the fixed jaw A to form a hammer, and also to form a projection a on the top part of the said jaw to form a turn-screw. I also utilize the ends of the handles B' and C' by forming holes D in them to fit small nuts or screw heads.

I wish it to be particularly understood that I do not limit myself to the precise details of construction hereinbefore described and illustrated by the accompanying drawings, but that I hold myself at liberty to make such changes and alterations as fairly fall within the spirit and scope of my invention.

I am aware that the adjustable jaws of adjustable spanners and wrenches have been locked to the shanks carrying the fixed jaws of such spanners and wrenches by means of cam levers and I do not therefore claim such as my invention, but

What I do claim, and desire to secure by Letters Patent, is—

1. In an adjustable spanner or wrench, the combination of a shank carrying a suitably shaped jaw at one end and a handle at the other end and having teeth or serrations formed on one of its edges, of an adjustable jaw adapted to slide on the said shank and provided with means for retaining its parallel motion thereon and prevent the front edge of its slot coming in contact with the teeth or serrations on the edge of the shank, of a gripping lever pivoted to the adjustable jaw and having a suitable handle, the gripping face of the said lever having teeth or serrations to engage with the teeth or serrations on the adjacent face of the shank carrying the fixed jaw, as and for the purpose set forth. 15
2. In an adjustable spanner or wrench, the combination of a shank carrying a suitably shaped jaw at one end and a handle at the other end and having teeth or serrations formed on one of its edges, of an adjustable jaw having a rear extension and adapted to slide on the said shank and provided with means for retaining its parallel motion thereon and prevent the front edge of its slot coming in contact with the teeth or serrations on the edge of the shank, of a gripping lever pivoted to the rear extension of the adjustable jaw and having a suitable handle, the 20
3. In an adjustable spanner or wrench, the combination of the shank B carrying the fixed jaw A at one end and a handle B' at the other end, and having teeth or serrations formed on one of its faces b; of the turn screw a formed on or fixed to the jaw A; of the adjustable jaw A' adapted to slide on the shank B and guided to retain its parallel motion thereon and prevent the front edge of its slot 25 coming in contact with the teeth or serrations on the face b of the shank by means of the guide piece a² fixed to the adjustable jaw A' and adapted to engage with one side of the slot b' in the shank B; of the gripping lever C pivoted to the adjustable jaw A' and having a suitable handle C', the gripping face c of the said lever having teeth or serrations to engage with the teeth or serrations on the face b of the shank B; and of the holes 30 D in the ends of the handles B' and C', all combined, arranged and operating as and for the purpose set forth. 35
